UNITED STATES PATENT OFFICE.

EDWIN F. HENDERSON, OF WEST ALLIS, WISCONSIN.

KEY-FASTENER.

SPECIFICATION forming part of Letters Patent No. 766,249, dated August 2, 1904.

Application filed January 22, 1904. Serial No. 190,245. (No model.)

To all whom it may concern:

Be it known that I, EDWIN F. HENDERSON, a citizen of the United States, residing at West Allis, in the county of Milwaukee and State 5 of Wisconsin, have invented a new and useful Key-Fastener, of which the following is a specification.

The invention relates to improvements in key-fasteners.

The object of the present invention is to improve the construction of key-fasteners and to provide a simple, inexpensive, and efficient device of great strength and durability designed for use on mortise-locks and capable 15 of effectually preventing an interiorly arranged key from being surreptitiously turned from the exterior with forceps or other means.

A further object of the invention is to provide a device of this character which after the 20 key has been placed in a lock and the engaging portion or lug turned up or away from the keyhole will substantially fill the latter and prevent a pick or other instrument from being introduced into the lock.

The invention has also for its object to provide a device of this character adapted to engage the inner escutcheon-plate and capable of adjustment to suit the space between a lock and such plate.

With these and other objects in view the invention consists in the construction and novel combination and arrangement of parts, as hereinafter fully described, illustrated in the accompanying drawings, and pointed out in 35 the claims hereto appended, it being understood that various changes in the form, proportion, size, and minor details of construction within the scope of the claims may be resorted to without departing from the spirit 40 or sacrificing any of the advantages of the invention.

In the drawings, Figure 1 is a vertical sectional view of a portion of a door having a mortise-lock and provided with a key-fastener constructed in accordance with this invention. Fig. 2 is a horizontal sectional view taken substantially on the line 2-2 of Fig. 1. Fig. 3 is a detail perspective view of the key-fastener. Fig. 4 is a side elevation, partly in 45 section.

Like numerals of reference designate corresponding parts in all the figures of the drawings.

1 designates a substantially oblong body portion consisting of a metal block or piece 55 adapted to be arranged in the keyhole of a lock 2 after the engaging portion of a key 3 has been turned up or away from the keyhole, as illustrated in Fig. 1 of the drawings, whereby the key is prevented from being surreptitiously turned from the exterior by means of forceps or the like. The block or piece also substantially fills the keyhole, and it effectually prevents a pick or other tool from being introduced into the lock. The ends of the 60 block or body project beyond the sides of the lock, as clearly shown in Figs. 1 and 2, and the inner end is preferably provided with projecting flanges 4, forming a head for engaging the outer face of the lock to limit the 65 movement of the key-fastener to prevent the same from being pulled through the keyhole from the exterior. The upper edge 5 of the body portion of the fastener is preferably 70 curved to form oppositely-tapered portions, 75 as shown in Figs. 1 and 3.

The body portion of the key-fastener is held in the lock by means of a pivoted fastening device or key 6, extending from the inner end of the body portion and having a 80 threaded stem or shank 7 and provided with a head. The threaded shank or stem extends into a threaded bore or opening 8 of the body portion of the fastening device, and the key extends longitudinally thereof from the inner 85 end of the same. The rotary fastening device is provided between the head and the shank, preferably at opposite sides, with lugs 9, adapted to engage the inner face of the inner escutcheon-plate 10; but a single lug may 90 be employed, as will be readily understood. The lugs are passed through the keyhole of the inner escutcheon-plate in an upright position, and the rotary fastener or key is then turned to bring the lugs into a horizontal position, as indicated in Fig. 3 of the drawings, 95 whereby the body portion of the key-fastener will be firmly held in the lock. The lugs 9, which engage the inner face of the inner escutcheon-plate 10 of the door, are 100

spaced from the head 6 of the rotary fastening device to form opposite notches, which receive the said inner escutcheon - plate 10. This will prevent the body portion from being forced inward or drawn outward. The threaded shank forms an adjustable connection and enables the rotary fastening device or key to be adjusted to suit the distance between the lock 2 and the inner escutcheon-plate 10.

Having thus fully described my invention, what I claim as new, and desire to secure by Letters Patent, is—

1. A key-fastener, comprising a body portion adapted to fit in the keyhole of a lock to prevent the key from turning, and locking means for retaining the body portion within the keyhole, said locking means being located wholly exteriorly of the lock, and comprising a fastening device extending from the inner end of the body portion and provided beyond the same with means for directly engaging a fixed portion of the door, substantially as described.
2. A key-fastener, comprising a body portion adapted to fit in the keyhole of a lock and

provided at its inner end with a shoulder for engaging the casing of the lock at the inner keyhole thereof to prevent the body portion from being drawn outward through the lock, and a fastening device extending from the inner end of the body portion and provided beyond the same with means for directly engaging the fixed portion of a door, whereby the body portion is retained in the keyhole, substantially as described.

3. A key-fastener, comprising a body portion adapted to fit in the keyhole of a lock to prevent the key from turning, and a rotary fastening device extending from the inner end of the body portion and provided beyond the same with a notch arranged to receive the inner escutcheon-plate or other fixed portion, whereby the body portion is retained in the keyhole of the lock, substantially as described.

In testimony that I claim the foregoing as my own I have hereto affixed my signature in the presence of two witnesses.

EDWIN F. HENDERSON.
